[57] CLAIM

The ornamental design for a telephone instrument, as shown and described.

DESCRIPTION

FIG. 1 is a perspective view of the telephone instrument, as seen from the front thereof;

FIG. 2 is a front elevational view of FIG. 1; and FIG. 3 is a perspective view of FIG. 1, showing the back of the instrument.

The telephone cord is shown broken away in part in FIGS. 1 and 3 for illustrative purposes only.
